UNITED STATES PATENT OFFICE.

THEODORE PONSAR, OF SOUTH OMAHA, NEBRASKA.

ALFALFA-GRINDER.

No. 908,801.

Specification of Letters Patent.

Patented Jan. 5, 1906.

Application filed November 27, 1906. Serial No. 345,408.

To all whom it may concern:

Be it known that I, THEODORE PONSAR, a citizen of the United States, and a resident of South Omaha, in the county of Douglas and State of Nebraska, have invented certain new and useful Improvements in Alfalfa-Grinders, of which the following is a specification.

My invention relates to machines for grinding alfalfa, clover or other forage crops, and it is the object thereof to provide in a machine of this class means for quickly and effectively cutting and breaking up the stems and tougher portions of the material, means for quickly removing the material from the grinding cylinders as soon as it is reduced to particles of the desired size, thereby avoiding undue pulverization of the leaves and more fragile portions of the material, means for keeping the material within the grinding cylinders constantly in the path of greatest destructive action, automatic vents for preventing clogging of the cylinders by too rapid feeding of moist and tough materials thereto, means for collecting and removing from the machine any pieces of metal or other refractory materials which may be by accident fed into the machine, and certain other novel constructions as will be more fully set forth hereinafter.

Constructions embodying my invention are shown in the accompanying drawings in which—

Figure 1 is a longitudinal sectional view of the mechanism, Fig. 2 is a sectional plan view of the same, Fig. 3 is a partial side elevation thereof, and Fig. 4 is a detail section of a portion of one of the perforated metal screens.

In the drawings 1, 1 represent suitable side plates having formed therein bearings 2 for the cylinder shafts 3 and 4. The toothed concave plates 5, 6, 7, 8 and 9, and the perforated metal screens 10, 11, 12, 13, 14 and 15 are secured between the side plates 1, being so arranged as to form intersecting cylindrical inclosures concentric with the cylinder shafts 3 and 4. Between the plates 16 is formed a feed opening which connects with the feed chute 17, as shown. The sheet metal shell or casing 18 is secured around the outer edge of the side plates to form an inclosed space between the same and the toothed concave plates and perforated metal screens. At the lower side of the machine 55 the said casing 18 merges into the exhaust chute 19 which is extended to and connected

with a suitable exhaust fan. The upper portions of the casing are hinged to the lower portions and may be swung outwardly, as indicated by the dotted lines in Fig. 1, to give access to the concave plates and screens.

Secured to the shafts 3 and 4, adjacent the side plates 1, are the spider wheels 32. Said wheels are provided on their outer rims with slotted radially extending lugs 30, to which the longitudinally extending toothed cylinder bars 21 are adjustably secured by the screws 22 passing through the slots in the lugs. On the ends of the shafts 3 and 4 are the belt pulleys 23 by which the cylinders are driven, both cylinders being arranged to revolve in the same direction, as indicated by the arrows A, A in Fig. 1. The teeth on the bars of each cylinder are so arranged as to pass between the teeth on the bars of the other cylinder at the arcs of intersection of the cylinders. The teeth on the concave plates are arranged to extend between the teeth of the cylinder bars, and at the ends of the cylinders toothed rings 24 are secured to the side plates 1, the teeth on said rings extending into notches in the ends of the cylinder bars, as shown in Fig. 2.

On the radial arms of the spider wheels are secured the fan blades 25, the same being so arranged that the forward faces thereof lie in the same planes as the faces of the corresponding cylinder blades. When the machine is in operation these blades 25, together with the cylinder blades, serve to keep the materials thrown outward from the centers of the cylinders, thus bringing said materials against the screens and into the interengaging teeth of the cylinder blades and concave plates. The said blades also assist in causing currents of air to be drawn into the central parts of the cylinders through the openings 26 in the side plates 1, and thence driven outwardly through the screens and the perforations in the concave plates, the said air currents carrying the material through the screens and plates as soon as it is reduced to particles small enough to pass through the perforations in the same.

One of the cylinders is of greater length than the other, the ends of the longer cylinder extending into the projecting portions 27 of the side plates 1, as shown in Fig. 2. In the side of each of said projecting portions 27 is an opening over which fits a gate 28 which is hinged above the opening and provided with a weight 29, arranged as shown in Figs.

2 and 3, the said weight normally holding the gate in closed position. When the machine is overloaded the excess of material tends to collect around the ends of the longer 5 cylinder thereby causing an internal pressure which opens the gates, as shown by the dotted lines in Fig. 3, permitting escape of the material and at the same time giving notice of the overload to the operator of the machine.

10 At the bottom of each of the cylinder casings and outside of the inner surfaces of the screens and concave plates is an open channel 30 which is extended through the side 15 plates 1, the openings to the channels being closed by plates 31, as shown in Fig. 3. The said channels are for the purpose of collecting any particles of metal, rock or other refractory materials which may be by accident 20 fed into the machine. Any of such materials which collect in the channels may be readily removed by taking off the plates 31 on each side of the machine and pushing a rod through the channel from end to end.

25 To lessen the probability of stems of the material passing endwise through the perforations of the screens I prefer to corrugate or roughen the inside of said perforations. The most convenient way in which this corrugation may be effected is by threading the 30 perforations in the screens, as shown by the enlarged detail view thereof in Fig. 4.

Now, having described my invention, what I claim and desire to secure by Letters Patent is:

1. In a machine of the class described, cylinder casings comprising alternately arranged screens and toothed concave plates, toothed cylinders revoluble in intersecting 40 arcs, the teeth of each cylinder being ar-

ranged to interengage with cutting action with the teeth of the concave plates and of the other cylinder, an inclosed exhaust space surrounding the screens and concave plates, and fan blades carried by the cylinders for the purpose set forth.

2. In a machine of the class described, toothed cylinders revoluble in intersecting arcs, a perforate casing surrounding said cylinders, said casing having teeth interengaging with cutting action with the teeth of the cylinders, an inclosed exhaust space surrounding said perforate casing, said exhaust space having an outlet for removal of the materials passing thereinto through the perforate cylinder casing, air inlet openings adjacent the axes of the cylinders, and means for drawing air into said openings and driving the same out through the perforate cylinder casing.

3. In a machine of the class described, cylinder casings comprising perforated metal screens and toothed concave plates, the perforations of the screens being corrugated or roughened as described, cylinders revoluble 65 within the casings, toothed bars carried by the cylinders and adjustably secured thereto, the teeth on the said bars passing with cutting action through the teeth of the concave plates and adjacent the inner surfaces of the 70 screens, and fan blades on the cylinders adjacent the toothed bars for the purposes set forth.

In testimony whereof I have hereunto subscribed my name in the presence of two witnesses.

THEODORE PONSAR.
